UNITED STATES PATENT OFFICE

JAMES N. SCHIEN, OF LOS ANGELES, CALIFORNIA

DESIGN FOR A PORTABLE LIQUID DISPENSER

Application filed August 12, 1930. Serial No. 36,636. Term of patent 3½ years.

To all whom it may concern:

Be it known that I, JAMES N. SCHIEN, a citizen of the United States, residing at Los Angeles, in the county of Los Angeles and State of California, have invented a new, original, and ornamental Design for Portable Liquid Dispenser, of which the following is a specification, reference being had to the accompanying drawing, forming a part thereof.

The ornamentation on the obverse side of Fig. 2 is a continuation of that disclosed in this figure.

I claim:

The ornamental design for a portable liquid dispenser, as shown and described.

JAMES N. SCHIEN.
